(57) CLAIM

The ornamental design for a storage box, as shown and described.

DESCRIPTION

FIG. 1 is a front, right, top perspective view of a storage box, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 2;

FIG. 10 is an enlarged view of detail 10 in FIG. 3;

FIG. 11 is an enlarged view of detail 11 in FIG. 8;

FIG. 12 is a front, right, top perspective view of the storage box in a detached state;

FIG. 13 is an enlarged view of detail 13 in FIG. 12; and,
FIG. 14 is an enlarged view of detail 14 in FIG. 12.

The dashed broken lines in the figures illustrate portions of the storage box that form no part of the claimed design.
The dash-dot-dash broken lines are for notating enlarged views and form no part of the claimed design.

1 Claim, 14 Drawing Sheets
